UNITED STATES PATENT OFFICE.

WILLIS W. HALE, OF CLEVELAND, OHIO.

AIR COMPRESSOR.

Application filed August 25, 1920. Serial No. 405,871.

To all whom it may concern:

Be it known that I, WILLIS W. HALE, a citizen of the United States, residing at Cleveland, in the county of Cuyahoga and State of Ohio, have invented certain new and useful Improvements in Air Compressors, of which the following is a specification.

The present invention relates to a device for compressing gaseous fluids such as air, and has for its object to provide a device of this character which embodies novel features of construction whereby a supply of the compressed fluid can be easily and quickly obtained with the expenditure of a minimum amount of power for driving the compressor.

Further objects of the invention are to provide a two stage compressor of this character which is comparatively simple and inexpensive in its construction, which can be readily assembled or taken apart, and which requires a minimum amount of power for its operation.

With these and other objects in view the invention consists in certain combinations, arrangements and associations of the parts, as will more fully appear as the description proceeds, the novel features thereof being pointed out in the appended claims.

For a full understanding of the invention reference is to be had to the following description and accompanying drawings, in which:

Figure 1 is a side elevation of a two stage air compressor which is constructed in accordance with the invention.

Figure 2 is a top plan view thereof, portions being broken away and shown in section to illustrate more clearly the details of construction.

Figure 3 is an end view of the compressor.

Figure 4 is a vertical longitudinal sectional view, showing the two compression chambers and the arrangement of the valves.

Figure 5 is a transverse sectional view on the line 5—5 of Figure 2.

Figure 6 is a detached perspective view of the reciprocating part of the compressor and the fixed inner piston, the latter being detached from the stem upon which it is mounted.

Figures 7, 8 and 9 are detail views of the valves.

Corresponding and like parts are referred to in the following description and

indicated in all of the views of the drawings by like reference characters.

Referring to the drawings, which illustrate one possible embodiment of the invention, the numeral 1 designates the outer cylinder which is horizontally disposed and provided with a foot portion 2 which is rigidly secured by suitable fastening members such as the bolts 3 to the base 4. The rear end of the cylinder is closed by a cylinder head 5, and the sides of the cylinder are formed with the corresponding longitudinally extending guide slots 6.

A hollow piston 7 is mounted to reciprocate within the cylinder 1, said hollow piston being in reality a combined piston and cylinder, since the exterior thereof operates as a piston within the outer cylinder 1, while the hollow interior 8 of the member 7 receives a fixed piston member 9 and in effect constitutes a cylinder for the said fixed piston. The forward end of the combined piston and cylinder 7 is provided with the usual piston rings 10 which enable a tight fit to be obtained within the fixed cylinder 1, and crosshead blocks 11 are detachably secured to opposite sides of the member 7 by suitable fastening means such as the screws 12, said blocks being slidably received within the longitudinal slots 6 of the cylinder 1. Studs 13 project from the blocks 11 and have the ends thereof removably threaded within the blocks, suitable set screws 14 being provided to prevent the studs from working loose. The outer periphery of the member 7, as shown more clearly by Figures 5 and 6 may be formed with a series of depressions 15 which are arranged in such a manner that they decrease the weight of the member without detracting in any manner from the strength and efficiency thereof.

The fixed piston 9 operates within the hollow interior of the reciprocating member 7, and is provided with the usual piston rings 16. This fixed piston is carried by a tubular stem 17, being indicated upon the drawings as having a threaded connection 18 with the said stem. This stem projects laterally from a standard 19 which is arranged at the open end of the fixed cylinder 1 and rigidly secured by the bolts 20 to the base 4. The stem 17 is indicated as threaded into a depression 21 formed in one side of the standard, and the tubular opening of the stem communicates with a passage 22 which extends upwardly through a fitting 23

provided for connection with a pipe leading to the tank or reservoir within which the compressed air is to be stored.

The head 5 of the fixed cylinder 1 is provided with an air inlet which is controlled by an inwardly opening check valve 24 such as that which is shown in detail by Figure 7. A spring which surrounds the tubular valve stem bears against a nut 26 and normally holds the valve in a closed position. However, the suction of the piston will open the valve during the outward portion of the piston stroke, and air will then flow through the tubular valve stem and the lateral outlets 27 provided at the base of the valve. The closed end of the combined piston cylinder member 7 is provided with a suitable inwardly opening check valve 28, such as that illustrated by Figure 8. The valve 28 is normally held upon its seat by the spring 29, although it will open inwardly to permit the passage of air from the fixed cylinder 1 into the interior of the combined piston cylinder 7. The fixed piston 9 is likewise provided with a suitable inwardly opening check valve 30 such as that illustrated by Figure 9. A spring 31 normally holds the valve in a closed position, although the valve will open inwardly to permit the passage of the compressed fluid from the interior of the combined piston cylinder member 7 to the tubular stem 17, this being the outlet from the compressor.

The standard 19 is provided with bearings 32 which receive a double crank shaft 33. One of the crank portions of this shaft is arranged upon each side of the compressor, and these crank portions are connected by the pitmen 34 to the before-mentioned studs 13 of the cross head blocks 11. With this construction it will be obvious that when the crank shaft is driven the combined piston cylinder member 7 will be reciprocated back and forth within the outer cylinder 1, and the double cross head and pitmen arrangement provides for a smooth even movement of the member without any binding or lost motion. The crank shaft 33 is extended at one side of the standard 19 and journalled in a bearing 35. This extended end of the crank shaft as shown is provided with a gear wheel 36 which is surrounded by a suitable guard member 37 and which meshes with a pinion 38 on the shaft on an electric motor 39. This is merely illustrative of one out of many manners in which the compressor may be driven. An oil cup 40 is applied to the top of the cylinder 1 and arranged to supply lubricant to the reciprocating member 7 as it is required. The outlet hose or pipe which leads from the compressor to the reservoir will be attached to the fitting 23 at the top of the standard 19.

In the operation of the device it will be

obvious that when the electric motor 39 is caused to operate the crank shaft 33 will be rotated and the reciprocating member 7 moved back and forth within the cylinder 1. Upon the outstroke of the member 7 air will be drawn into the cylinder 1 through the check valve 24. Upon the instroke of the member 7 this air will be initially compressed between the member 7 and the cylinder head 5. The initial compression of the air will force it through the check valve 27 into the interior of the combined piston cylinder member 7. It will be seen by reference to the drawings that the interior of the member 7 is much smaller than the interior of the cylinder 1, and that the air will accordingly be considerably compressed as it is forced into the interior of the member 7. Upon the next outstroke of the member 7 a fresh supply of air will be drawn into the cylinder 1, and the initially compressed air within the interior of the member 7 will be further compressed between the closed end of the said member 7 and the fixed piston 9. This further and final compression of the air forces it through the check valve 30 into the tubular opening of the stem 17, and this compressed air is conveyed through a suitable pipe or conduit to the reservoir in which the air is being stored. It will thus be obvious that the air is compressed by stages, the first stage or initial compression taking place in the cylinder 1, while the second stage or final compression takes place in the interior of the reciprocating member 7. Both the in and out strokes of the reciprocating member 7 are compression strokes, and the compressor thus offers a comparatively uniform resistance to the motor or drive means, with the result that the mechanism operates with a smooth, even action and a minimum amount of power is required to drive the same. For the purpose of supplying lubricant to the interior of the reciprocating member 7 this member is provided with an opening 7^a which at certain times is brought under the opening of the oil cup 40 so that the lubricant will be supplied to both the interior and the exterior of the hollow reciprocating member 7.

While one possible embodiment of the compressor has been illustrated and described in detail, it will be understood that numerous modifications and changes can be made in the details of construction without departing in any manner from the spirit of the invention.

Having thus described the invention, what I claim as new and desire to secure by Letters Patent is:—

1. A multiple stage compressor including a fixed cylinder provided with a valve controlled inlet and having guide slots in the sides thereof, a hollow piston mounted to reciprocate within the fixed cylinder and

- provided with a valve controlled passage, blocks projecting from the hollow piston and received within the before-mentioned slots, a fixed piston arranged to fit within the hollow piston and provided with a valve controlled outlet, the initial compression taking place within the fixed cylinder while the final compression takes place within the hollow piston, a standard supporting the fixed piston, a crank shaft journalled upon the standard, and an operative connection between the crank shaft and the hollow piston.
2. A multiple stage compressor, including a fixed cylinder having slots in the sides thereof, a hollow piston mounted to reciprocate within the fixed cylinder, blocks projecting from the sides of a hollow piston and received within the slots of the fixed cylinder, a fixed piston arranged to project within the hollow piston, the initial compression taking place within the fixed cylinder and the final compression taking place within the hollow piston, valve controlled ports being provided to permit of the passage of the fluid through the elements of the compressor in one direction, a standard supporting the fixed piston, a double crank shaft journalled upon the standard, pivot studs projecting from the blocks of the hollow piston and pitmen connecting the said pivot studs to the crank portions of the shaft.
3. A multiple stage compressor, including a base, a fixed cylinder arranged longitudinally upon the base and having slots in the sides thereof, a hollow piston mounted to reciprocate within the fixed cylinder, blocks projecting from the sides of the hollow piston and received within the slots of the fixed cylinder, a standard projecting from the base at one end of the fixed cylinder, a tubular stem carried by the standard and extending longitudinally into the fixed cylinder, a fixed piston mounted upon the tubular stem and operating within the hollow piston, a double crank shaft journalled upon the standard, pitmen connecting the crank shaft to the blocks at opposite sides of the hollow piston, and means for applying power to the crank shaft, the initial compression taking place within the fixed cylinder, and the final compression taking place within the hollow piston, valved controlled ports being provided to permit of the passage of the fluid through the elements of the compressor in one direction.
- In testimony whereof I affix my signature.

WILLIS W. HALE.
